CLAIM

We claim the ornamental design for a coffee brewer, as shown and described.

DESCRIPTION

FIG. 1 is a perspective view of a coffee brewer showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The evenly broken lines in the figures depict portions of the coffee brewer that form no part of the claimed design. The long-dash/short-dash boundary line in FIGS. 1, 6, and 7 indicates a boundary between claimed portions of the coffee brewer, and portions that form no part of the claimed design. The long-dash/short-dash boundary line and the areas within it form no part of the claimed design.
